TOILET

Joseph F. Wolpert, New Brunswick, N. J.

Application December 20, 1937, Serial No. 180,669

15 Claims. (Cl. 4—13)

This invention relates to toilets and also to a novel valve therefor. In one of its aspects the invention is directed to a novel toilet, reservoir and valve assembly. The invention finds especial utility in that the toilet is a sanitary unit whose outside surface may be readily cleaned, the installation of the same may be accomplished even by a person unskilled in the art of connections, the assembly of the valve itself may be done in an easy and ready manner, the valve may be readily combined with its associated part, the toilet may be connected to any size water line leading into the bathroom, the valve is very rugged and will not get out of order under normal conditions of use, and if for any reason it does get out of order, repairing it is a very simple and easy matter.

Figure 1 represents a side view of a toilet embodying my invention.

Figure 2 represents a horizontal cross sectional view taken on line 2—2 of Figure 1 in the direction of the arrows.

Figure 3 represents a vertical cross sectional view taken on line 3—3 of Figure 2.

Figure 4 represents a vertical cross sectional view showing the valve located in a reservoir, together with the operating mechanism for the valve.

Figure 5 represents a cross sectional view taken on line 5—5 of Figure 4 in the direction of the arrows.

Figure 6 represents a longitudinal cross sectional view taken on line 6—6 of Figure 2, with the flush valve removed.

As shown in the drawings, there is a toilet bowl 10 having an annular conduit 11 at the upper end thereof, with the conduit 11 having a plurality of spaced parts or opening 12 at the lower side thereof. An apron 13 extends downwards and forwardly from the under side of conduit 11 and its free end extends below the level of the water normally contained in the bowl 10. A normal discharge pipe 14 is located at the rear and may be connected to the usual sewer pipe. The bowl 10 has a plurality of reservoirs 15, 16, 17, 18, 19 and 20 located below the lower level of said conduit 11 and formed in two batteries and it is a single-unitary structure which may be composed of porcelain or the like. These reservoirs are closed and connected in series by conduits 21, 22, 23, 24 and 25 which are located near the bottoms of these reservoirs. An inlet passage 26 near the upper end of chamber 15 is adapted to be connected to the city line 27. A vertically disposed opening 28 at the bottom of the chamber 15 ex-

tends downwardly to a horizontally disposed conduit 29 connecting the same to a vertically and centrally disposed conduit 30 having its other end opening into the annular chamber 11. This continuous passageway 28—29—30 is the flush line from the chamber 15 to the distributing annular chamber 11.

Located in the chamber 15 is a flush valve resting on a somewhat resilient rubber bushing 31 extending into passage 28 and forming a water tight seal therewith. A metallic expansion bushing 32 is forced into the bushing 31 and forces the side of bushing 31 to bear snugly against the passageway 28. The bushing 31 has an enlarged upper end with a shoulder seating on the bottom of chamber 15 and litharge or other appropriate material is applied to the lower face of the shoulder and sides of the bushing so that a water tight seal is formed between the bushing and lower part of chamber 15 at opening 28. The upper or enlarged end of the bushing 31 forms a seat for the valve.

The novel valve comprises a one piece housing member of bronze or the like including a cylindrical member 31 and box like projection 34 communicating therewith. The upper end of the housing is in the form of a cover 35 integral with the sides of the box projection 34 and the cylindrical member 33. And, a guide member 36 is integral with the cover 35 and has a portion thereof spaced from the upper face of the cover 35. Both the cover 35 and member 36 have centrally disposed and vertically aligned cylindrical openings adapted to accommodate a cylindrical valve stem 37 having a pair of spaced ears 38 at its lower end. The valve 39 has a bearing face whose contour is a part of a sphere so that the same may readily close the flush passage 28, by automatically finding its own bearing surface on the upper edge of the rubber bushing 31. The upper part of the valve has a plurality of stops 40 to limit the amount of upward travel of the valve and it also has a tongue 41 located between the ears 38. A pin 42 passes through the ears 38 and tongue 41 and the size of the opening in the tongue 41 through which pin 42 passes is somewhat greater than the diameter of the pin 42 so that the valve 39 is loosely and freely pivoted thereon. The upper and outer end of box projection 34 has a pair of upstanding ears 43. A loosely fitting plate gate 44 with a plurality of openings 45 therein near the lower edge thereof and a weighting projection 46 on the outer face thereof has a tongue 47 located between the ears 43 and projecting upwardly thereabove. A pin 55

48 extends through the ears 43 and tongue 47. The diameter of the opening in the tongue 47 through which pin 48 extends is slightly greater than the diameter of pin 48 so that the gate 44 is freely pivoted thereon.

5 A bar 49 has one end located and loosely fitting between the cover 35 and guide 36 and has an opening therein aligned with the vertical openings in the cover 35 and guide 36. The stem 37 10 which passes through these three openings is of such a diameter that it passes freely through these three openings, and the diameter of the opening in the bar 49 is such that there is a real loose fit between the stem 37 and bar 49 for the 15 reasons hereinafter fully explained. The other end of bar 49 is in the form of a pair of ears 50 between which the tongue 47 is located and a pin 52 extends through the ears 50 and tongue 47, with the size of the opening in tongue 47 20 through which pin 52 passes being slightly greater than the diameter of pin 52. A demountable cylindrical casing 51 having a slot therein to accommodate the bar 49 is mounted on the cover 35 by pressing the same over the projection thereon and is maintained in position by friction although it may be keyed or bolted or in some other manner secured thereto.

25 A yoke 55 has a threaded nut 56 making a threaded connection with the threaded upper 30 end of stem 37. The upper end of casing 51 has a pair of diametrically opposed vertical slots accommodating a shaft having an eccentric 57 for actuating the yoke 55 upon rotation of eccentric 57. The shaft has guide projections 58 for 35 maintaining the eccentric 57 in proper position with respect to the upper cross arm of yoke 55. On one end of said shaft is U member 59 whose legs are located in the openings of an H element 60 of the mechanism for actuating said shaft. The size of the opening defined by the yoke 55 40 is sufficient so that said shaft may be removed therefrom. A cover plate 61 caps the upper end of the casing and it has a right hand threaded member 62 integral therewith and extending upwardly and centrally thereof.

45 A hand screw member 63 whose lower half is 50 interiorly threaded to accommodate the right hand threads of member 62 and whose upper half is interiorly threaded to accommodate left hand threads makes threaded connections with member 62 and a left hand screw threaded member 64 having a positioning and locking element 65 integral therewith. As shown, by rotating the hand screw in one direction, the bearing element 65 may be brought downwardly towards the cover 61, and if it is rotated in the other direction, the bearing element is moved away from the cover 61 and towards the top of chamber 15. This particular construction may be used to demountably 60 mount the valve in the chamber 15. The hand screw is so rotated that the bearing element 65 is forced against the top face of chamber 15 to maintain the valve in position.

65 An enlarged opening 70 extends from the outside of the unit to the chamber 15. This provides a passageway through which the valve may be inserted and mounted in the chamber 15. A cover plate 71 encloses this opening and is maintained in position by bolts 72, there being a 70 gasket 73 located between the plate 71 and the porcelain unit in order to provide a water tight seal. At the center of the cover plate and integral therewith there is a housing 74 through which passes a shaft 75 having the H member 75 60 integral therewith at the inner end thereof.

Secured to the outer end of shaft 75 is a handle 76 for rotating the shaft. A water tight joint between the housing 74 and shaft 75 is maintained by packing 77 located at the inner end of housing 74 and pressed forwardly by a bushing 78 actuated by spring 79 held in position by member 88.

5 A spring 80 is mounted on the outside of the porcelain unit and under the handle 76 and urges the handle 76 upwardly against the stop 10 81. In practice the toilet and valve may be assembled either in the shop or at the place of use. If it is assembled in the factory, the assembly may be taken to the place of use and be mounted therein in a very short period of time. 15 The unitary, single element may have a passageway 90 extending from an inner wall thereof to the passage 29. Connected to this passageway 90 and to the discharge pipe is a valve chamber having an inclined seat 91. A gate valve 92 is 20 loosely pivoted at the upper end of said chamber and is adapted to close the passageway between the passage 29 and discharge pipe upon being forced over to the inclined seat 91. The rear of the unit may be placed flush against the wall 25 of the bathroom with the valve 82 of the city water line 27 being located in a vertical slot 83 at the rear of the unit. This line is connected to the inlet 26 communicating with the chamber 15 and the discharge pipe 14 is connected to the 30 normal sewer pipe. Thus, all the installation is completed now merely by affixing the porcelain unit to the flooring if desired.

35 In operation with the valve 82 open, water flows in the closed chamber 15 and then to the 40 other closed chambers 16, 17, 18 and 19. Water continues flowing into these chambers until the pressure of the air cushions formed in these chambers prevent the flow of any more water into them from the city line. Thus, each chamber 45 contains water under pressure. When the handle 76 is pushed downwardly, the shaft 75 is rotated. The shaft 75 rotates the H member 60 which is integral therewith.

50 The H member 60 upon rotation causes the U member 59 to rotate. And, rotation of U 55 59 causes rotation of eccentric 57. Rotation of eccentric 57 bearing against the upper cross arm of yoke 55 and causes the yoke 55 to be lifted. As the yoke is moved upwardly by the eccentric 57, the stem 37 and the valve 39 are carried upwardly therewith until the stops 40 strike the bottom of cover 35. With the valve 39 spaced from its seat of bushing 31, the water under pressure in the six chambers flows into and through the bushing 32. Because of the pressure of this water on the outside of the plate gate the gate is subjected to a force in the direction of arrow A and this force is transmitted to the bar 49 which is now subjected to a force in the direction of arrow B and towards the opening in the side of chamber 15 to maintain by friction the stem 37 60 in upper position whereby the valve 39 is maintained in open position even after the lever 76 is released and returned to its original position. 65 When the valve 39 is in open position, the water is automatically forced from the chambers through the bushings 31 and 32 then through the conduits 28—29—30 of the flush line to the distributing chamber 11, then through the ports 12 70 and bowl 10 to the discharge outlet 14. After a predetermined quantity of water, say 3-8 gallons, has flushed the bowl, the pressure of the water on gate 44 has so decreased, that its force transmitted to bar 49 is insufficient to hold the 75

stem 37 in its upper position and consequently the valve and stem together with the yoke automatically drop to their original positions. The only outlet 31 from the chambers in series now being closed, the water from the city line keeps entering until the original pressure again builds up. The water from the city line enters the chambers even when the flush discharge takes place. The valve 82 is not closed at any time except when the toilet is to be disconnected. Thus the pivoted gate 46 controls the position of the valve 39 once it is raised.

When the pressure of the water in the tank is above a predetermined amount, the gate 46 is swung inwardly towards the valve so that it pulls the bar 49 to hold the stem 37 in elevated position by friction. After a certain amount of water goes through the flush line, and notwithstanding the continuous feeding of water thereto during flushing, the pressure of the water in the chambers is lessened to such a degree that the force of the water on gate 46 transmitted to bar 49 is insufficient to maintain the stem 37 in this position and the stem and valve automatically drop to their original positions.

During the discharge of water from said chambers to said bowl, the pressure of the water which enters outlet 90 closes valve 92 against seat 91 to prevent the same from escaping. If, however, the toilet after use is to be disconnected from the city line, the valve 82 is closed, then the handle 76 is actuated to open valve 39. After discharge of water from the chambers to the flush bowl, the handle 76 is maintained in lower position to maintain the valve open whereupon the water remaining in the chambers will not discharge into the flush bowl, but being at reduced pressure insufficient to close the valve 92 will "leak" out of the discharge pipe depending from the bowl.

What is claimed is:

1. A toilet comprising a flush bowl, a closed chamber having an opening therein adapted to be connected with a source of water supply for said toilet, a passageway for conducting water from said chamber to said bowl, and means for controlling the discharge from said chamber to said bowl, said means including a manually operable valve adapted to be moved to open position whereby the water in said chamber flows from said chamber through said passageway and to said bowl, and means acted upon by the pressure of the water in said chamber for maintaining said valve in said open position, said valve automatically moving to closed position, to prevent the discharge of water from said chamber to said bowl, when the pressure of said water acting on said last mentioned means has been reduced by the discharge of said water from said chamber.

2. A toilet comprising a flush bowl, a closed chamber having an opening therein adapted to be connected with a source of water supply for said toilet, a passageway for conducting water from said chamber to said bowl and means for controlling the discharge from said chamber to said bowl, said means including a valve, which when in closed position and with said chamber connected to the source of supply, the chamber is partially filled with water and the remainder of the space therein is occupied by an air cushion, manually operable means for moving said valve from closed to open position whereby the water in said chamber discharges into said bowl, and means acted upon by the pressure of the

water in said chamber to maintain said valve in open position, said last means rendered ineffective to maintain said valve in said open position when the pressure of said water in said chamber has been reduced to a predetermined value upon discharge of water therefrom.

3. A toilet comprising a flushing bowl, a closed chamber having an opening therein adapted to be connected with a source of water supply, a passageway connecting said chamber to said bowl for conducting water from said chamber to said bowl, and means for controlling the discharge of water from said chamber to said bowl, said means including a manually operable valve adapted to be moved to open position whereby the water in said chamber flows from said chamber to said bowl, a member connected to said valve and movable from one position to another upon actuation of said valve, and means associated with said member and acted upon by the pressure of the water in said chamber to maintain said member in its particular position when said valve is at open position whereby said valve is maintained in open position, said valve and member adapted to return to their original positions to prevent the flow of water from said chamber to said bowl when the pressure of said water on said means is so reduced that the action of said water pressure on said means is ineffective to maintain said member in said particular position when the valve is at open position.

4. A toilet comprising a flush bowl, a closed chamber having an opening therein adapted to be connected with a source of water supply for said toilet, a passageway from conducting water from said chamber to said bowl, means for controlling the discharge from said chamber to said bowl, said means including a valve for opening and closing said passageway, said valve adapted to be manually operated to open position whereby the water flows from said chamber to said bowl, a valve stem associated with said valve and adapted to move in unison with said valve, means acted upon by the pressure of the water in said chamber to frictionally engage said stem in its particular position when the valve is in open position to maintain said valve in said open position, said valve adapted to automatically return to its closed position and said stem to automatically return to its original position after discharge of said water from said chamber when the pressure of the water in said chamber has been so reduced that its action on said means is ineffective to maintain said stem in said particular position whereby said valve automatically closes said passageway.

5. A toilet including a flush bowl, a closed chamber having an opening therein adapted to be connected to a source of water supply for said toilet, a flush passageway for conducting water from said chamber to said bowl and means for controlling the discharge from said chamber to said bowl, said means including a valve, a vertically disposed valve stem connected to said valve and adapted to be moved therewith, said valve and stem adapted to be moved vertically to move said valve from close to open position, and means acted upon by the pressure of the water in said chamber to engage said stem in its particular position when said valve is at open position to maintain said valve at said open position, said means including a member adapted to be actuated in a horizontal plane and a pivoted member adapted to actuate said first member, the movement of said second mem-

ber dependent on the pressure of the water in said chamber, said stem adapted to return to its original position and said valve adapted to return to close position when the pressure of the water on said second member is ineffective to maintain the stem in its upper position by the first member after discharge of water from said chamber.

5. A toilet comprising a flush bowl, a closed chamber having an opening therein adapted to be connected with a source of water supply for said toilet, a passageway for conducting water from said chamber to said bowl and means for controlling the discharge from said chamber to said bowl, said means including a valve, which when in closed position and with said chamber connected to the source of supply, the chamber is partially filled with water and the remainder of the space therein is occupied by an air cushion, 10 manually operable means for moving said valve from closed to open position whereby the water in said chamber discharges into said bowl, automatic means for rendering said manually operable means ineffective, and means acted upon by the 15 pressure of the water in said chamber to maintain said valve in open position when said manually operable means has been rendered ineffective, said last means rendered ineffective to maintain said valve in said open position when the pressure of 20 said water in said chamber has been reduced to a predetermined value upon discharge of water therefrom.

6. A toilet comprising a flushing bowl, a closed chamber having an opening therein adapted to be connected with a source of water supply, a passageway connecting said chamber to said bowl for conducting water from said chamber to said bowl, and means for controlling the discharge of water from said chamber to said bowl, said 35 means including a manually operable valve adapted to be moved to open position whereby the water in said chamber flows from said chamber to said bowl, automatic means for rendering said manually operable means ineffective, a member connected to said valve and movable from one 40 position to another upon actuation of said valve, and means associated with said member and acted upon by the pressure of the water in said chamber when said manually operable means has been 45 rendered ineffective to maintain said member in its particular position when said valve is at open 50 position, said valve and member adapted to return to their original positions to prevent the flow 55 of water from said chamber to said bowl when the pressure of said water on said means is so reduced that the action of said water pressure on said means is ineffective to maintain said member in said particular position when the valve is at 60 open position.

7. A toilet comprising a flush bowl, a closed chamber having an opening therein adapted to be connected to a source of water supply for said toilet, a passageway for conducting water from 65 said passageway to said bowl, a valve, which when in closed position and with said chamber connected to said source of supply, the chamber is partially filled with water and the remainder of the space therein is occupied by an air cushion, 70 manually operable means for lifting said valve from closed to open position whereby the water in said chamber discharges through said passageway to said bowl, said means including a lifting cam, automatic means for returning said cam to 75 its original position whereby said cam is rendered

uneffective, means acted upon by the pressure of the water in said chamber to maintain said valve in open position when said cam has been rendered ineffective, said last means rendered ineffective to maintain said valve in open position when the pressure of the water in said chamber has been reduced to a predetermined value upon discharge of water therefrom whereupon said valve returns to its close position.

8. A toilet including a flush bowl, a closed chamber having an opening therein adapted to be connected to a source of water supply for said toilet, a flush passageway for conducting water from said chamber to said bowl, a valve for said passageway, a stem secured to said valve, a guide for said stem located in and supported by said chamber, manually operable means for actuating said stem to move said valve from closed to open position whereupon the water in said chamber discharges through said flush passageway to said bowl, pivoted means actuatable by the pressure of the water in said chamber to frictionally engage said stem to maintain said valve in open position, said valve and stem adapted to return automatically to their original positions when the pressure of the water in said chamber is so reduced by the discharge of water therefrom that the pressure on said pivoted means is insufficient to maintain said valve and stem in open position.

9. A toilet comprising a flush bowl, a closed chamber having an opening therein adapted to be connected to a source of water supply for said toilet, a flush passageway for conducting water from said chamber to said bowl, a valve for said passageway, a housing for said valve, said housing supported by said chamber, a stem for said valve, said valve pivoted to said stem, a guide for said stem, said guide supported by said housing, manually operable means for raising said valve and stem to open said passageway whereby the water in said chamber discharges through said passageway to said bowl, and pivoted means supported by said housing and acted upon by the pressure of the water in said chamber to maintain said stem and valve in raised position, said pivoted means rendered ineffective to maintain said valve and stem in raised position when the pressure of the water in said chamber has been reduced to a predetermined value upon discharge of water therefrom whereupon said valve and stem automatically return to their original position to close said passageway.

10. A toilet comprising a flush bowl, a closed chamber having an opening therein adapted to be connected to a source of water supply for said toilet, a flush passageway for conducting water from said chamber to said bowl, a valve for said passageway, a stem for said valve, said stem pivotally connected to said valve, a housing for said valve, a guide for said stem, said guide carried by said housing, a yoke secured to said stem, manually operable means for raising yoke, stem and valve to raise said valve from closed to open position whereby water may discharge from said chamber through said passageway to said bowl and means acted upon by the pressure of the water in said chamber to maintain said valve in said open position, said last means supported by said housing and including an element pivoted thereto, said last means rendered ineffective to maintain said valve in open position when the pressure of the water in said chamber on said pivoted element has been reduced to a predetermined value upon discharge of water therefrom

whereupon said yoke, stem and valve are lowered to close said passageway.

12. A toilet comprising a flush bowl, a closed chamber therein adapted to be connected with a source of water supply for said toilet, said opening located between the top and bottom of said chamber, a passageway for conducting water from said chamber to said bowl, said passageway communicating with said chamber and bowl and connected to the bottom of said chamber, demountable means for controlling the discharge from said chamber to said bowl, said means adapted to be inserted and removed as a unit and comprising a valve, a stem pivotally connected to the valve and a water pressure actuatable means for controlling the position of the valve, said chamber being partially filled with water and the remainder of the space therein being occupied by an air cushion when said valve is in closed position, manually operable means for raising said stem and valve to open position whereby the water in said chamber discharges through said passageway to said bowl, said water pressure actuatable means acted upon by the pressure of the water in said chamber to frictionally engage said stem to maintain said valve and stem in open position, automatic means for rendering said manually operable means ineffective, said pressure actuatable means rendered ineffective to maintain said valve in open position when the pressure of the water in said chamber has been reduced to a predetermined value upon discharge of water therefrom whereupon said stem and valve return to close position.

13. A toilet comprising a flush bowl, a closed chamber having an inlet opening therein adapted to be connected to a source of water supply for said toilet, a passageway for conducting water from said chamber to said bowl, a valve for said passageway to control the discharge of water from said chamber to said passageway, said chamber being partially filled with water, the remainder of the space in said chamber occupied by an air cushion when said valve is in close position, a stem pivotally connected to said valve, a yoke connected to said stem, a shaft extending into said chamber, a cam supported by said shaft, said shaft being manually operable to rotate said cam to actuate said yoke and stem upwardly and move the valve from close to open position whereby the water in said chamber will discharge through said passageway into said bowl, automatic means for returning said cam to ineffective position, means acted upon by the pressure of the water in said chamber, when said cam is returned to ineffective position, to frictionally engage said stem and maintain said valve in open position, said last means rendered ineffective to maintain said valve in open position when the pressure of the water in said chamber has been reduced to a predetermined value upon discharge of water therefrom, whereupon said yoke and

stem are lowered to return said valve to close position.

14. A toilet comprising a flush bowl, a discharge conduit therefor, a closed chamber having an opening therein adapted to be connected to a source of water supply for said toilet, a passageway for connecting said chamber to said bowl, means for controlling the discharge from said chamber to said bowl, said means including a valve, which when in closed position and said chamber connected to said source of supply, the chamber is partially filled with water and the remainder of the space therein is occupied by an air cushion, manually operable means for moving said valve from closed to open position whereby the water in said chamber discharges through said passageway and into said bowl, means acted upon by the pressure of the water in said chamber to maintain said valve in open position, said last means rendered ineffective to maintain said valve in said open position when the pressure of said water in said chamber has been reduced to a predetermined value upon discharge of water therefrom whereupon said valve returns to its close position, a conduit communicating with said discharge conduit and said passageway and a valve for controlling the passage of water from said passageway to said conduit.

15. A toilet comprising a flush bowl, a discharge conduit therefor, a closed chamber having an opening therein adapted to be connected to a source of water supply for said toilet, a passageway for connecting said chamber to said bowl, means for controlling the discharge from said chamber to said bowl, said means including a valve, which when in closed position and said chamber connected to said source of supply, the chamber is partially filled with water and the remainder of the space therein is occupied by an air cushion, manually operable means for moving said valve from closed to open position whereby the water in said chamber discharged through said passageway and into said bowl, means acted upon by the pressure of the water in said chamber to maintain said valve in open position, said last means rendered ineffective to maintain said valve in said open position when the pressure of said water in said chamber has been reduced to a predetermined value upon discharge of water therefrom whereupon said valve returns to its close position, a conduit communicating with said discharge conduit and said passageway and a valve for controlling the passage of water from said passageway to said conduit, said second valve closing said conduit by the pressure of water thereon during normal discharge of water from said chamber to said bowl, said valve being open when the pressure of the water entering said conduit is below a predetermined value whereupon the water passes to the discharge conduit when the pressure of the water discharging from said chamber is below a predetermined value.

JOSEPH F. WOLPERT.
